(57) **CLAIM**

The ornamental design for a sun shade, as shown and described.

DESCRIPTION

The claimed sun shade is used to provide shade from the sun. FIG. 1 is a front and side perspective view of a sun shade showing my new design;

FIG. 2 is a side elevation view thereof; (other side is identical)

FIG. 3 is a front elevation view thereof;

FIG. 4 is a rear elevation view thereof; and,

FIG. 5 is a plan view thereof.
